US00D461247S

(12) **United States Design Patent** (10) Patent No.: **US D461,247 S**
 Dragan et al. (45) Date of Patent: ** Aug. 6, 2002

(54) **COMBINED APPLICATOR DEVICE AND
DISCHARGE NOZZLE FOR DENTAL
MATERIAL PLACEMENT**

(75) Inventors: **William B. Dragan**, Easton; **John J. Disccko, Jr.**, Trumbull, both of CT (US)

(73) Assignee: **Centrix, Inc.**, Shelton, CT (US)

(**) Term: **14 Years**

(21) Appl. No.: **29/129,771**

(22) Filed: **Sep. 21, 2000**

(57) **CLAIM**

The ornamental design for a combined applicator device and discharge nozzle for dental material placement, as shown and described.

DESCRIPTION

FIG. 1 is a perspective view of a combined applicator device and discharge nozzle for dental material placement showing our new design. The broken line showing is for illustrative purposes only and forms no part of the claimed design.

FIG. 2 is a side elevation view thereof, the other side being the same;

FIG. 3 is a top view thereof, the bottom view being the same;

FIG. 4 is a front end view thereof; and,

FIG. 5 is a rear end view thereof.
